(57) **CLAIM**

The ornamental design for a beverage brewing device, as shown and described.

DESCRIPTION

FIG. 1 is a perspective view of a beverage brewing device showing my new design;

FIG. 2 is a front view thereof;

FIG. 3 is a back view thereof;

FIG. 4 is a left side plan view thereof;

FIG. 5 is a right side plan view thereof;

FIG. 6 is a bottom plan view thereof; and,

FIG. 7 is a top plan view thereof.

The broken lines are directed to environment and are for illustrative purposes only.

The broken lines form no part of the claimed design.
